UNITED STATES PATENT OFFICE

121,773

DESIGN FOR A WEATHER VANE OR SIMILAR ARTICLE

Edward McClure, Chicago, Ill., assignor to F. P.
Smith Wire & Iron Works, Chicago, Ill., a corporation of Illinois

Application March 15, 1940, Serial No. 90,938

Term of patent 3½ years

To all whom it may concern:

Be it known that I, Edward McClure, a citizen of the United States, residing at Chicago in the county of Cook and State of Illinois, have invented a new, original, and ornamental Design for a Weather Vane or Similar Article, of which the following is a specification, reference being had to the accompanying drawing forming a part thereof, in which

Fig. 1 is a side elevation of a weather vane or similar article, showing my new design, and

Fig. 2 is an end elevation thereof.

I claim:

The ornamental design for a weather vane or similar article, as shown.

EDWARD McCLURE.
